UNITED STATES PATENT OFFICE

THOMAS J. FEGLEY AND GEORGE O. LEOPOLD, OF PHILADELPHIA, PENNSYLVANIA, ASSIGNORS TO NORTH BRO'S MFG. CO., OF PHILADELPHIA, PENNSYLVANIA, A CORPORATION OF PENNSYLVANIA

DESIGN FOR A PORTABLE POWER-DRIVEN SAW FRAME

Application filed December 13, 1929. Serial No. 33,785. Term of patent 14 years.

To all whom it may concern:

Be it known that we, THOMAS J. FEGLEY and GEORGE O. LEOPOLD, citizens of the United States, residing in Philadelphia, Pennsylvania, have invented a new, original, and ornamental Design for a Portable Power-Driven Saw Frame, of which the following is a specification, reference being had to the accompanying drawing, forming part there-

of, in which the figure is a perspective view of a portable power-driven saw frame showing our new design.

We claim:—

The ornamental design for a portable power-driven saw frame, substantially as shown.

THOMAS J. FEGLEY.
GEORGE O. LEOPOLD.
